BATHTUB HOOD OR SIMILAR ARTICLE

Henry Dreyfuss, South Pasadena, Calif., assignor to Crane
Co., Chicago, Ill., a corporation of Illinois

Application September 8, 1958, Serial No. 52,540

Term of patent 14 years

(Cl. D4—4)

Fig. 1 is a perspective exterior view of the bathtub hood or similar article embodying my design;

Fig. 2 is a top view thereof;

Fig. 3 is a front view thereof; and

Fig. 4 is a transverse sectional view taken on the line 4-4 of Fig. 3.

The portions shown in dotted lines are for purpose of illustration only.

I claim:

The ornamental design for a bathtub hood or similar article, substantially as shown and described.
